UNITED STATES PATENT OFFICE.

JOHN GABEL, OF CHICAGO, ILLINOIS.

AUTOMATIC TALKING MACHINE

1,414,563.

Specification of Letters Patent. Patented May 2, 1922.

Application filed January 4, 1916. Serial No. 70,131.

To all whom it may concern:

Be it known that I, JOHN GABEL, a citizen of the United States, and a resident of the city of Chicago, county of Cook, and State of Illinois, have invented certain new and useful Improvements in Automatic Talking Machines, of which the following is a specification.

The invention relates to automatic talking or sound reproducing machines in which mechanism is provided for changing the records and for shifting the sound box or reproducer. The invention seeks to provide improved record shifting mechanism by which record discs of different sizes are automatically shifted into and out of playing position upon a rotatable record support or turn-table, and to provide improved means for automatically controlling the movement of the sound box or reproducer so that it will properly co-operate with record discs of different sizes.

A further object of the invention is to provide improved means for rotating the turn-table or record support and for operating the record and sound box shifter mechanism.

With these and other objects in view, as will presently appear, the invention consists in the features of improvement hereinafter set forth, illustrated in the preferred form in the accompanying drawings and more particularly pointed out in the appended claims.

In the drawings: Figure 1 is a view in front elevation of the improved machine, certain parts being broken away for the sake of clearness. Fig. 2 is a rear elevation of the main parts of the machine. Fig. 3 is a plan view with parts in section on the lines 3-3 of Figs. 1 and 2. Fig. 4 is a vertical section on an enlarged scale on the lines 4-4 of Figs. 1 and 2, with certain parts omitted. Fig. 5 is a front elevation on an enlarged scale of the parts for controlling the operation of the machine. Fig. 6 is a plan view, and Fig. 7 is an end view of the mechanism shown in Fig. 5, parts being shown in section on lines 6-6 and 7-7, respectively, of Fig. 5. Fig. 8 is an enlarged plan view of portions of the record and sound box shifter mechanisms, parts being shown in section on lines 8-8 of Fig. 9. Fig. 9 is a view in vertical elevation of the same with parts shown in section on lines 9-9 of Figs. 2 and 8 re-

spectively. Fig. 10 is a view similar in part to Fig. 9, but with the sound box shown in shifted position. Fig. 11 is an enlarged detail view in rear elevation of parts of the sound box or reproducer shifter mechanism. Fig. 12 is an enlarged detail view in front elevation of the sound box shifter mechanism with the sound box shown in dotted lines in different positions. 65

While the details of the broad features of the present invention may be widely varied, the preferred embodiment of this invention is similar in many respects to the automatic machine set forth in Letters Patent of the United States No. 1,184,603, dated April 6, 1915, and No. 1,182,551, dated May 9, 1916.

The improved machine is mounted upon a framework and is enclosed in a suitable casing that is not shown but may be somewhat similar to that illustrated in said prior patent. The framework shown comprises upper and lower, substantially rectangular, cast metal frames 1 and 2 which are connected at their corners by vertical rods 3 and which are also connected intermediate their ends and at the front and rear of the machine by vertical straps 4. A horizontal cast metal frame 5 is arranged in the lower portion of the framework, is fixed to the upright rods and straps 3 and 4 and carries many of the operating parts of the record and sound box shifter mechanism. A cast metal frame 6 secured to the vertical straps 80 above the frame 5 carries the record support or turn-table and parts of its drive mechanism. The entire framework is removably mounted within the casing and preferably upon lugs 7 (see Fig. 1) which are secured to the end walls of the casing. 85

The record support or turn-table A is mounted in the upper central portion of the framework upon the upper end of a short vertical shaft α that is journaled in suitable bearings formed in the frame 6 (see Figs. 3 and 4). The turn-table is driven by a small electric motor, governor-controlled friction gearing being interposed to maintain the speed of the turn-table uniform. In the 105 preferred construction shown, the vertical turn-table shaft α is connected by a pair of beveled gears 8 to a short horizontal shaft 9 journaled in the frame 6 in the rear of the turn-table shaft and provided with a large 110 spur-gear 10 which meshes with a pinion 11 on a horizontal shaft 12. The latter is jour-

naled in uprights 13 and 14 on the frame 5, extends from the rear towards the front of the machine and is provided at its forward end with a friction disc 15. A co-operating 5 friction disc 16 is mounted on the left-hand end of a longitudinally extending, horizontal shaft 17. This shaft is journaled in the upper ends of a pair of arms 18 which are pivoted at their lower ends upon lugs on the 10 frame 5. Springs 19 engage these arms and hold the friction disc 16 in proper frictional engagement with the disc 15.

The opposite end of the shaft 17 is provided with a grooved pulley 20 that is connected by a belt 21 to a grooved pulley 22 on the shaft of a small electric motor C which may be conveniently mounted in the bottom of the casing in which the machine is enclosed. The hub of the pulley 20 is 20 fixed to the shaft 17, but the hub of the friction disc 16 is connected by a pin or key to the shaft to rotate therewith and is free to shift longitudinally on the shaft so that it will engage the co-operating friction disc 15 25 at different distances from the center of the latter. The position of the friction disc 16 is determined by a fly-ball governor comprising a series of weighted spring arms B which are fixed at their ends to the hubs of the 30 friction disc and of the pulley 20. By the mechanism described, the turn-table A is driven by the electric motor C and the governor B and co-operating friction discs (which are interposed in the connections between the motor and the turn-table) serve 35 to compensate for any variations in the speed of the electric motor and thereby maintain the speed of the turn-table uniform.

Preferably, an additional governor is provided for controlling the speed of the record support or turn-table. For this purpose a fly-ball governor D is mounted on a shaft 23, the latter being arranged in front of the turn-table shaft a and journaled in suitable 45 bearings in the frame 6. The governor shaft 23 is provided with a small pinion 24 which meshes with the teeth of a gear 25 that is fixed to the turn-table shaft a. The fly-ball governor D controls a friction disc d 50 which bears against felt or like pads on the inner end of a brake arm or lever d'. The latter is pivoted at its outer end to a lug on the frame 6 and rests on an adjusting screw 26. The brake arm or lever d' may be 55 adjusted in well-known manner to vary the speed of the turn-table or record support, but in any given adjustment cooperates with the friction disc d and fly-ball governor D to maintain the speed of the turn-table uniform. The disc records are preferably carried in a pair of magazines or record holders E and E' which are arranged on opposite sides of the turn-table A. Except 60 for the fact that these record holders or 65 magazines are adapted for holding relatively

large and small record discs,—for example, record discs that are 10 and 12 inches in diameter, respectively,—the construction thereof and of the operating mechanism therefor is quite similar to that set forth 70 in the prior patent and the application above referred to. In the present construction, the left-hand record holder or magazine E is designed to hold relatively large, or 12-inch, records e and the right-hand magazine 75 E' is adapted to hold relatively small or 10-inch records e'.

Each magazine comprises a frame having a series of inwardly projecting fingers 27 upon which the records e are supported one 80 above another. The frame of each magazine is mounted to slide upon a pair of guide rods 28 (see Figs. 1 and 3) which are fixed at their upper ends to the frame 1 and at their lower ends to the frame 5. Anti-friction 85 rollers 29 at the upper ends of the magazine frames engage the outer sides of the guide rods 28 and anti-friction rollers 30, mounted on the lower ends of the magazine frames, engage the inner sides of such rods. Cords 90 31 attached to each magazine extend upwardly over guide pulleys 32 and thence downwardly to the outer ends of a pair of levers 33. The latter are pivotally mounted at their inner ends on the lower frame 2 and 95 counter-balancing springs 34 are connected at their outer ends to said levers and at their inner ends are connected by a pair of adjusting screw bolts 35 to a lug or arm 36 that depends from the lower frame 2, (see Fig. 5). 100

As in the construction set forth in the prior application above referred to, the magazines are vertically shifted to bring any one of the records thereon in line with the turn-table by a pair of horizontally disposed arms 105 f (see Figs. 1, 2 and 3) which are pivoted at their inner ends to the upright 13 (see Fig. 2) on the intermediate horizontal frame 5, and the outer ends of which engage a pair of inwardly projecting arms 38 in the lower 110 ends of the respective record magazines. A pair of shafts f', journaled in the frame 5, are provided with heart-shaped cams F which are arranged to engage abutment lugs 39 on the arms f and shift the latter and the 115 record magazines. By rotating one or the other of the heart-shaped cams F, the corresponding arm f and magazine E are shifted to bring any one of the records in the latter opposite the turn-table. Preferably, the 120 edges of the cams F are provided with beveled recesses which co-operate with the beveled ends on the abutment lugs 39 to accurately position the record magazines with one of the records in each in line with the 125 turn-table. The cams are held in proper position by ratchet wheels 40 which are fixed to the cams and are engaged by roller pawls 41 mounted on the ends of a pair of arms 42. The latter are pivotally mounted on the up- 130

per end of the part 13 and are spring-pressed to yieldingly hold the rollers 41 in engagement with the ratchet wheels 40 and thereby accurately hold the cams F and the record 5 magazine E in adjusted position. The teeth of the ratchet wheels are so shaped that the heart-shaped cams may be turned in right-hand direction but are held against movement in the opposite direction. The outer 10 ends of the arms f move between a pair of vertical guide pins 43 (see Figs. 1 and 3) which are fixed to the horizontal frame 5.

The records in each record holder or magazine are held against displacement by pairs 15 of stationary, vertically disposed pins 44 and 45. The lower pins 44 are fixed on the outer ends of a pair of triangular brackets 46 that project laterally from the frame 6; but the upper pins 45 are detachably connected at 20 their upper ends to the upper horizontal frame 1. These pins extend through the central openings usually provided in disc records and prevent the displacement of the records as the magazines are raised and lowered. The adjacent ends of the pins 25 are, however, spaced apart so that the record in line with the turn-table can be shifted in horizontal direction. By removing the upper pins 45, the records in the magazines 30 can be readily changed.

The records are shifted between the magazines and the turn-table by a horizontal slide or carriage G which is preferably formed of an aluminum casting. As most clearly 35 shown in Figs. 3 and 8, this slide comprises two curved holders g and g' which are centrally connected by the main body of the slide and which are also connected by straight tangential front and rear portions 40 47. The left-hand holder g of the slide is of such size that it will extend nearly around the large records e and the right-hand holder g' is adapted to similarly engage one of the small records e'. The slide as a whole is of 45 such length that one of the holders will engage a record in position on the turn-table and the other holder will engage the record in one or the other of the magazines which is in line with or opposite the turn-table. The 50 carriage is arranged to slide back and forth upon front and rear horizontal track bars 48 which are fixed to the uprights 3 and 4 of the framework, the ends of the carriage being provided with rollers 49 which rest upon the 55 upper edges of the track bars and the central portion of the carriage being provided with rollers 50 that extend beneath the edges of the track bars.

The slide or carriage G is moved back and 60 forth by a shift lever H (see Fig. 2) which is pivotally mounted at its lower end on the rear portion of frame 2 and the upper slotted end of which engages a pin or roller on a lug 51 that depends from the rear central 65 portion of the slide. The shift lever H is

provided intermediate its ends with a cam-slot h (see Fig. 2), having a curved intermediate rib 52, and an operating crank arm h' is provided with a pin or roller 53 which projects within the cam-slot. The crank arm 70 h' is fixed to the rear end of a horizontal shaft J which extends from front to rear of the machine and is journaled in suitable bearings on the horizontal frame 5. This shaft constitutes the main drive shaft of 75 the record shifting mechanism and carries a gear j fixed thereto and a drum j' which is loose on the shaft (see Figs. 1, 2 and 6). As most clearly shown in Fig. 1, the drum is provided with ratchet teeth and a pawl 54 80 pivoted on the gear j is spring-pressed into engagement with the ratchet teeth of the drum so that the gear and shaft J will be driven, when the drum is rotated, in left-hand direction. A small wire rope or cord 85 55 is wrapped about the drum and is fixed thereto at one point by a screw 56 (see Fig. 6). One portion of the cord extends horizontally from the drum and is connected to the inner end of a spring 57, the outer end 90 of which is fixed to the frame. The opposite end of the cord extends downwardly and is connected to the inner end of a lever k. The latter extends toward the right-hand side of the machine and is pivoted at its 95 outer end upon a lug 58 that projects upwardly from the end of the frame 2. A heavy motor spring K is connected to the inner end of the lever k and the lower end of this spring, as set forth in the patent 100 above referred to, is fixed to the bottom of the casing in which the machine is enclosed. This spring is wound up or placed under tension by lifting the lever k in manner hereinafter described. During this upward 105 movement of the lever, the drum j' is rotated by the spring 57 and the ratchet teeth thereon pass idly beneath the pawl 54. On the downward movement of the lever, effected by the motor spring K, the drum 110 ratchet j' drives the gear j through the medium of the pawl 54 and thereby operates shaft J, crank arm h' and carriage shift lever H. The motor spring K is, of course, 115 considerably stronger than the spring 57 which merely serves to take up any slack in the small wire rope or cord 55.

A fly-ball governor L controls the speed of operation of this motor mechanism. This 120 governor (see Figs. 1 and 4) is mounted on a short horizontal shaft L' in front of the drum j', and a small pinion 59 on the rear end of this shaft engages a gear 60 on a horizontal counter-shaft 61. The rear end of the latter is provided with a small pinion 62 (see Fig. 3) which meshes with the teeth of the gear j. As usual with fly-ball governors of this type, the governor L is provided with a friction disc 64 which co-operates with a brake 65 to regulate and main- 125 130

tain the speed of operation of the shifter mechanism uniform.

The starting and stopping of the shifter mechanism are under the control of a stop-dog M (see Figs. 1, 5, 6 and 7) which is pivoted at 66 on the horizontal frame 5 and the outer pointed end of which is arranged to engage the teeth of a ratchet 67 which is fixed to the gear 60, to thereby hold the shifter mechanism against operation. The stop-dog M is also provided with a rearwardly projecting lug m which engages a pair of semi-circular ribs m' that are fixed to the front face of the gear j (see Figs. 1 and 6).

The stop-dog M is held in its normal or lowered position with its outer end in engagement with the ratchet 67 by means of a spring 68 which engages an arm 69 which projects upwardly from the pivoted end of the stop-dog. In this position the lug m extends between the ends of the segmental ribs m' which are spaced apart to receive it. The lever or arm k is raised to place the motor spring K under tension, and, at the end of this movement, the lever k engages an arm M' which extends downwardly from the pivoted end of the stop-dog M, thereby lifting the stop-dog and lug m thereon and releasing the shifter mechanism so that it will be operated by the motor spring K. During this movement, the gear j is rotated, as described, and the stop-dog is held in elevated position, since the lug m thereon rests upon one of the segmental ribs m'. At the end of a half revolution of the main shaft J of the shifter motor mechanism, the lug m will drop into the other space between the ribs m' and the stop-dog M is returned to normal position by the spring 69 to arrest the shifter mechanism. Preferably, also, the stop-dog is provided with a projecting spring finger 70 which co-operates with the brake 65 of the governor L to release and arrest the latter as the stop-dog is raised and lowered. In this way, half revolutions are imparted to the main shaft J at successive operations of the machine, and the crank arm h' on its rear end serves to alternately shift the lever H and the carrier G in opposite directions.

As shown in the drawings, the carriage or slide G is at the left-hand side of the machine and all of the large records e are in position in the magazine E, while one of the small records e', which has been withdrawn from the magazine E', is in position on the turn-table. In this position, the magazine E can be shifted vertically by the corresponding cam F to bring any desired record into position within the holder g of the carriage and between the pins 44 and 45. At the next operation of the machine, the carriage G will be moved to the right-

hand side of the machine and the selected record e from the magazine E will be moved into playing position on the turn-table or record support A. At the same time the record e' on the turn-table will be moved back into its position in the right-hand magazine E'. Mechanism is provided for preventing the movement of the magazine from which a record has been withdrawn. For this purpose, and as described in Patent No. 1,182,551 above referred to, the cams F and ratchet wheels 40 which are fixed thereto are loosely mounted on the shafts f' and the hubs of the cams are provided with clutch teeth which are arranged to be engaged by a pair of clutches 71 (see Figs. 3 and 6) which are keyed to rotate with the shaft, but are shiftable axially thereon. These clutches are shifted by a pair of pivoted, spring-held levers 72, the inner ends of which are spring-pressed into engagement with the flange 73 on the rear face of gear j. This cam is provided at one point with a notch 74 which is arranged to be alternately engaged by the levers 72 as the gear j is rotated a half revolution at a time at the successive operations of the machine. The parts are so arranged that the clutch of the full magazine (the left-hand magazine E in the position shown in the drawings) is engaged and the clutch of the magazine from which a record is withdrawn (the right-hand magazine E' in the position shown) is disengaged. The shafts f' project through the front of the enclosing casing and are provided with knobs or the like, so that the user of the machine can shift the full magazine to select the next record. Means are also provided for automatically shifting the record magazines. For this purpose, as set forth in the patents above referred to, the crank arm h' on the rear end of the shaft J is provided at its end with a dog 75 (see Fig. 2) which is arranged to co-operate alternately with the ratchet wheels 40 and rotate the same a step at a time at the successive half revolutions of the shaft J. Thus, the magazines can, if desired, be shifted by the user of the machine to select the records to be played, but if no selections are made by the user, the record shifting mechanism will operate automatically to play all the records in the machine in succession.

When a record is on the turn-table, it is held in central position thereon by a pin N (see Figs. 8 and 9) which is mounted upon the forward end of a horizontal arm n and is adapted to extend through the central opening of the record into a socket in the turn-table. The arm n is fixed at its rear end to the upper end of a vertically shifting rod n' (see Fig. 2) which is guided at its upper end in bracket 76 fixed to the rear upper portion of the framework and at its lower

end in a strap 77 secured to the horizontal frame 5. The lower rounded end of the shifter rod n' engages a spiral cam 78 that is fixed to the rear end of a horizontal shaft 79. The latter is journaled in brackets 80 (see Fig. 4) that depend from the frame 5 and at its forward end is provided with a gear 81 which is connected by an intermediate idler 82 to the gear j . The gear 81 is one-half the size of the gear j , so that, as the latter rotates through a half revolution at each operation of the shifter mechanism, the gear 81 and cam 78 are rotated through a complete revolution. When the shifter mechanism is started, the cam 79 quickly lifts the rod n' , arm n and pin N , so that the record on the turn-table can be moved by the sliding carriage G back to the position in its magazine and another record on the opposite magazine moved into playing position on the turn-table and beneath the pin. At the end of the movement of the carriage, the cam 78 lowers the bar n' and thereby brings the pin N into engagement with the new record on the turn-table. The shifter rod n' is held in engagement with the cam 78 by a spring 83 connected thereto and to the frame 5.

After the slide or carriage G has been shifted to place a record on the turn-table, it is moved backward to a slight extent, so that it will not contact with such record while the latter is played or reproduced. For this purpose a pair of arms 84 are provided on the upper portions of the frame 6 and are connected thereto by springs 85 (see Figs. 3 and 8). At the end of the movement of the carriage G in one or the other direction, the lug 51 thereon engages one or the other of the arms 84 and places the corresponding spring 85 under tension. At this point, the pin or roller 53 on the crank arm h' passes over a high point on the cam slot h of the shifter lever H , and the spring 85, which has been placed under tension, then acts to impart a slight movement in backward direction to the carriage, so that parts of one or the other of the holders g or g' will be moved out of engagement with the record on the turn-table, as shown in Fig. 8. It is, of course, understood that the parts of the holders g and g' which engage the edges of the records are slightly larger in diameter than the records themselves. As the records pass between the turn-table and the magazines, they are upheld by pairs of guide lugs 86 which project upwardly from the frame 6 on opposite sides of the turn-table (see Figs. 1 and 4). As the records of either size vary slightly in diameter, the center pin L and the pins 44 and 45 are provided with pointed ends so that they will properly engage the holes in the records and center the same on the turn-table and on the magazines.

A sound box or reproducer P is mounted upon the forward end of a hollow arm P' by which it is connected in any suitable manner to an amplifying horn or the like. In the construction shown, the arm P' terminates at its rear end in an elbow having a sleeve-like portion 87 which engages a guide-rod 88. The rear end of the sound box arm P' is also connected by a vertical pivot screw 89 to a yoke 90 which is provided with upturned ears 91 that engage and slide upon the guide-rod 88. The ears 91 snugly fit the guide-rod 88 but the sleeve 87 of the sound box arm loosely fits thereon so that it may vibrate horizontally on the pivot 89 to a slight extent, as it is moved along the guide rod, and thereby allow the stylus of the sound box to accurately follow the groove of the record. A centering spring 92 is coiled about a pin 93 on the upper rear portion of the yoke 90, and the forwardly curved ends thereof pass over a pair of lugs 94 on the yoke and engage the ends of the sleeve-like portion 87 of the sound box arm. This spring serves to yieldingly hold the sound box arm in central position on the yoke. Both the sound box arm P' and the yoke 90 can be swung in vertical direction upon the guide-rod 88.

A feed screw 95 is journaled in the bracket 76 below and in front of the guide-rod 88, and a lever 96 pivoted on the yoke 90 is provided at its forward end with a segmental nut 97 which is adapted to engage the feed-screw. A spring 98 extends between the rear end of the lever 96 and a pin 99 that projects rearwardly from the elbow of the hollow arm P' and serves to yieldingly hold the nut 97 in engagement with the feed-screw 95. The latter is connected by a pair of beveled gears 100 (see Figs. 2 and 4) to the upper end of a short vertical shaft 101 that is journaled in the bracket 76, and the lower end of the shaft is connected by a pair of beveled gears 102 to a short horizontal shaft 103 journaled in the frame 6. A pinion 104 fixed to the forward end of the shaft 101 is connected by a gear 104' to a gear 105 on the shaft 9. As the turn-table and record thereon are rotated, the feed-screw 95 is driven by the gearing described to move the sound box or reproducer over the record.

When a new record is placed in position on the turn-table, the sound box or reproducer is lifted and moved outwardly to starting position and lowered into engagement with the outer portion of the record. For this purpose, a track bar R (see Figs. 8, 9 and 12) extends beneath a lug r on the lower rear portion of the sound box. The outer end of this track bar is pivoted to an arm 106 that depends from the top frame 1. Its inner end extends through the notch on the underside of the arm n and a lug 107 on the arm n is provided with a pin 108

that projects through a vertical slot in the track bar. A spring 109 also connects the inner end of the track bar to the arm n and tends to lift the same, but the inner end of the track bar is adapted to be held in a depressed position, as hereafter described, by a spring-held catch 110 which is pivoted on the arm n and adapted to engage the end of the track bar.

- 10 The track bar is raised, when the arm n is lifted, by the shifter rod n' , and the engagement of the track bar with the lug r on the sound box lifts the latter to the position shown in Fig. 10. This movement also tilts 15 the yoke 90 on the guide-rod 88 and, as the rear portion of the yoke overlaps the lever 96, the segment nut 97 is lifted out of engagement with the feed-screw 95. The sound box and sound box arm are then 20 moved outwardly over the record, this movement being guided by the track bar R and guide-rod 88.

The return shift of the sound box arm is effected by a lever S (see Figs. 2, 9 and 11) 25 which engages a slotted lug 111 on the yoke 90 and is pivoted at its lower end on the lower portion of the bracket 76. This lever is operated from the shifter arm n' by a yielding connection comprising a lever preferably formed of two parts S' and S'' both pivoted at 111' to the bracket 76. The parts S' , S'' ordinarily move together and are connected by a spring 112 that holds the lever S' in engagement with the lug 113 on 30 the lever S'' . The free end of the lever S' rests upon a stud 114 (see Fig. 2) on the shifter rod n' and is connected by a spring 115 to a projection on the pivoted end of the shifter lever S . The levers S and S'' are 35 provided with a pair of co-operating lugs 116 and 117 (see Fig. 9) which are normally out of alignment. When the shifter rod n' is first lifted, it raises the levers S' and S'' and levers the lug 116 in front of the lug 117 so that the shift lever S cannot move. 40 This movement of the shift lever also raises the sound box and disengages the nut from the feed-screw, as already described. The continued upward movement of the shifter 45 rod n' and of the levers S' and S'' places the spring 115 under tension and, when the lug 117 passes by the lug 116, the return shift lever S is actuated by the spring 115 to throw the sound box and reproducer arm outwardly toward the edge of the record on 50 the turntable. When the shifter rod n' , arm n and track bar r are lowered, the stylus or needle of the sound box is engaged with the record, in readiness to reproduce the same, 55 and the segment nut 97 is at the same time re-engaged with the feed-screw 95. At the same time the levers S' and S'' are lowered to the position shown in Fig. 2, and the tension is relieved on the spring 115. The 60 shifter arm S is then returned slowly to the 65

position shown in Fig. 2, as the sound box is fed across the record. By providing the two levers S' , S'' that are yieldingly connected, these parts are not apt to become broken when the sound box is shifted by hand in 70 making repairs or the like.

It is necessary to arrest the outward movement of the sound box at different distances from the center of the turn-table, so that the sound box needle will properly engage the periphery of a large 12-inch, or a small 10-inch record. For this purpose, a relatively fixed stop T and a shiftable stop T' are provided for arresting the return movement of the sound box. The relatively 75 fixed stop T is mounted on the depending arm 106 (see Figs. 4, 8 and 12) and, if desired, may be provided with an adjusting screw 118. The shiftable stop T' is journaled on a short shaft t which is mounted 80 in the arm 106 and in the bracket 76. This stop is provided with a depending arm t' , and a spring 119 fixed to the part 106 is arranged to engage flattened faces on the hub of the stop T' to thereby hold the stop either 85 in the horizontal position shown, or in a vertical position, depending from the shaft t . In the position shown, the stop T co-operates with a lug 120 on the sound box arm P' and arrests the outward movement of the 90 sound box arm in proper position to play a small 10-inch record. When the carriage or slide G is moved to the right-hand side of the machine to remove the small record e' from the turn-table and place a large record e thereon, an upwardly projecting lug 121 on the central portion of the carriage strikes the depending arm t' and turns the shiftable stop T' downwardly out of operative position. Then, when the sound box 95 is shifted outwardly, it will not be arrested until it engages the relatively fixed stop T . On the shift of the slide or carriage in the opposite direction, or toward the left, to place a small record e' on the turn-table, the 100 lug 121 will strike the stop T' and move it back to operative position, so that the outward movement of the sound box will be arrested in proper position to engage the periphery of the small record. The sound 105 box or reproducer can thus be arrested at different distances from the center of the turn-table without breaking any of the parts, since the return shift lever S is yieldingly actuated by the spring 115, as previously 110 described.

The shifter mechanism also serves to change the needle or stylus of the sound box. For this purpose, as set forth in the 115 patent No. 1,182,551 above referred to, the sound box is provided with a projecting finger 122 which, as the sound box is lifted, passes through a slot 123 in a cam-plate 124 that depends from bracket 125 on the top frame 1. Ordinarily, there are two needles, 120

one above the other, in the needle holder 126 of the sound box, the lower needle, which is in use, being firmly held in place by a spring-held clamp 127. As the sound box is 5 raised, the clamp 127 and a pivoted, spring-held ejector 128 on the sound box are engaged by a pair of lugs 129 and 130 on the cam-plate 124 to thereby release and eject the lower, used needle and move the upper, 10 new needle into the grip of the clamp 127. At the same time a needle is ejected from a suitable needle magazine 132 (see Fig. 2) by means of a spring-held actuating dog 133 which is mounted on the horizontal 15 arm n (see Fig. 8.) As fully set forth in the application above referred to, the needle from the magazine passes through a guide-tube 134 on the sound box and into the needle holder 126.

20 In the construction shown, the turn-table is rotated from electric motor C through the medium of the governor-controlled friction gearing, and the shifter mechanism is operated by the motor spring K, instead of 25 being operated by the electric motor. But the latter is used to wind up or place the motor spring K under tension. For this purpose, a small wire rope or cord 135, connected to the lever arm k' , extends upwardly 30 over a small drum 136 on a horizontal, longitudinally extending shaft 137. This shaft is journaled in fixed lugs 138 on the frame 5 and is provided at its outer end with a gear 139 which is adapted to mesh with a pinion 35 140 that is loosely mounted on the shaft 17. A clutch member W, on the shaft 17, is connected to the pinion 140 by a sleeve 141. The pinion and clutch member are slidable on the shaft and the latter co-operates with 40 clutch teeth formed on the pulley 20 to thereby throw the means for winding up the motor spring K into and out of operation. A clutch shifting lever W' (see Figs. 1, 3 and 4) is pivoted at 142 on an upwardly 45 projecting part 143 on the frame 5 and is provided, as usual, with a forked forward end having pins thereon that engage an annular groove in the clutch member W. A fixed vertical pin 144 on the part or 50 bracket 143 extends through a horizontal slot at the forward end of the shift lever W' and limits its throw. A spring 145 extends between the fixed pin 144 and a pin 146 on the rear end of the shift lever and, 55 as the lever is oscillated on its pivot 142, this spring shifts across this pivot or axis and serves to complete the shift of the lever and clutch in either one or the other direction and to yieldingly hold these parts in 60 the position into which they are shifted. The forward end of the lever is provided with a pin 147 which engages the short horizontal slot in one end of a link 148. The other end of the link is pivoted to the 65 upwardly projecting part 69 of the stop

arm M (see Fig. 1), and by this means the lever W' is shifted to disengage the clutch.

The clutch is moved back into engaged position by a shifter rod 149 which co-operates with the pin 146 on the rear end of the 70 shift lever. The part 149 is pivoted at one end on the forward end of a lug 150 that projects forwardly from the lower end of a crank arm 151. The latter is fixed to a shaft 152 that is journaled in the upper 75 portion of the frame 6. The rear end of this shaft is provided with an upwardly projecting crank arm 153 that is pivotally connected to a sliding link or rod 154. The latter is guided in a horizontal direction in the 80 frame 76 and is provided at its end with an out-turned portion or lug 155 that projects through an opening in the frame 76, as shown in Figs. 2, 3 and 11.

85 In the position shown in the drawings, with the sound box or reproducer at the inner end of its movement adjacent the center of the turn-table, the lug 155 is engaged by a projection 156 on a short lever 157. This lever, as most clearly shown in Figs. 90 9 and 11, is pivotally mounted and is free to slide to a limited extent on a short horizontal rod 158 which is fixed to the lower portion of the yoke 90. The forward end of this lever is provided with a segment nut 95 159 that is adapted to co-operate with the end threaded portion 95' of the feed-screw 95 and which is separated from the main threaded portion by an annular groove or recess 160. A spring 161, connected to the 100 outer end of the lever 157 and to a pin 162 on the rear end of the reproducer arm, tends to force the nut 159 into engagement with the feed screw. But a horizontal pin 163 on the rear end of the lever 96 is arranged to 105 engage the rear end of the lever 157 and serves to hold the nut 159 out of engagement with the feed-screw until the nut 97 on the lever 96 drops into the groove or recess 160 of the feed screw. When this occurs, the 110 nut 159 engages the threaded portion 95' of the feed screw and is shifted thereby to move the lug 156 against the lug 155, and so move the slide or rod 154 and the parts connected thereto to the position shown in 115 the drawings. A return spring 164 for these parts is connected to the slide or rod 154 and to the frame 76 (see Figs. 2 and 3). In the position shown in the drawings, this return spring is held under tension. 120 The shifter rod 149 (see Fig. 3) is connected to the frame by a spring 165. This holds the outer end of the rod against the pin 146 on the shift lever W' and against a pin 166 which is fixed to the underside of 125 one of the brackets 46. The shifter 149 is provided with an inclined cam face 167 that co-operates with the pin 146 and is also provided with a notch 168 which is arranged to co-operate with the pin 146 130

to shift the clutch lever W' and thereby throw the clutch W into engaged position.

In the drawings, the carriage G , as stated, is shown at the left-hand side of the machine with one of the small records e' withdrawn from the right-hand magazine E' . In this position, the right-hand heart-shaped cam F is disconnected from its shaft f' so that the magazine E' must remain in proper position to receive the record on the turn-table at the next operation of the machine. But the left-hand cam F is connected to its shaft and the latter can be adjusted to shift the left-hand magazine E and bring any one of the records e therein into engagement with the holder g of the carriage. The other parts of the machine are shown in the position assumed after the clutch W is thrown into its engaged position, so that the drum 135 is driven from the electric motor C to raise the lever k and place the actuating spring K of the shifter motor under tension. During this winding movement the ratchet teeth on the drum j' , as stated, pass idly beneath the pawl 54, but at the end of its upward movement the lever k strikes the part M' and lifts the stop arm M to permit the operation of the shifting mechanism. At the same time the link 148, which is connected to the part 69 of the stop-arm, is shifted so that the lost motion between it and the pin 147 (see Fig. 3) of the clutch shifter W' is taken up and the latter is then moved to disengage the clutch W . As stated, the spring 145 assists in completing this disengaging shift of the clutch and holds it in disengaged position. Preferably, also, this upward movement of the stop arm M is arranged to interrupt the flow of current through the electric motor C , so that the turn-table is not rotated during the operation of the shifter mechanism. For this purpose the end of the stop arm M is provided with a forwardly extending pin 169 which extends through a slot in the end of a lever X . The latter is pivoted upon the upper end of a bracket 170 that is suitably secured to the lower front portion of the framework. This bracket and the parts mounted thereon, are omitted from Fig. 1 for the sake of clearness, but are shown in Figs. 5, 6 and 7. A knife-blade switch X' is connected by a pivot pin 170' to the left-hand portion of this bracket and co-operates with a pair of insulating contacts X'' also mounted on bracket 170 to open and close the circuit of the motor C . A spring 171 connected to the switch tends to hold it in closed position. The hub of the switch is provided with a curved arm 172 having a lug 173 thereon and which is arranged to be engaged by a projection 174 on the end of lever X . When the stop arm M is raised, the lever X is shifted and the lug 174 thereon engages the lug 173 on the switch X' and

thereby shifts it against the tension of the spring 171 to open position. The stop arm M , as noted, is held in raised position by the engagement of the lug m thereon with one of the flanges m' of the gear j , as described, until the latter has completed a half revolution, so that the circuit of the motor C is held open during the operation of the shifter mechanism.

As described, the half rotation of the shaft J and crank h' on its rear end operates the slide or carriage G through the medium of the shaft lever H , to thereby move the record on the turn-table back into its magazine and withdraw a new record from the opposite magazine and place it on the turn-table. At the end of the movement of the slide or carriage, it is given a slight backward movement, as described, by one or the other of the spring-actuated levers 84. During the half revolution of the gear j , the cam rib 73 thereon having the notch 74 co-operates with the levers 72 to disengage the clutch 71 of the magazine from which the record is withdrawn, and re-engage the clutch of the magazine into which the record on the turn-table is returned, so that this full magazine can then be shifted to select the record to be played at the succeeding operation. At the end of the movement of the carriage, the dog 75 on the end of the crank arm h' engages the ratchet wheel 40 corresponding to the full magazine and shifts it and the heart-shaped cam F one step, so that the full magazine is thus automatically shifted one step to select a new record for the next operation of the machine, even though no selection is made, by manually rotating the corresponding shaft f' .

The half revolution of the shaft J rotates the cam 78 through a complete revolution, as described, and thereby raises the shifter rod n' , arm n thereon and center pin N to release the record on the turn-table, and at the same time lift the inner end of the track bar R and thereby raise the sound box to the position shown in Fig. 10. The sound box is thus moved past the cam-plate 124 which actuates the needle clamp 127 and ejector 128 to change the needle, and the segment nuts 97 and 159 are lifted out of engagement with the feed-screw 95. As soon as the nut 159 on the lever 157 is thus lifted out of engagement with the part 95' of the feed screw, the spring 164 shifts the sliding rod 154 and the lug 155 thereon outwardly and moves the lever 157 outwardly along the pin 158. This shift of the sliding rod, effected by the spring 164, also moves the rock arm 153, shaft 152 and rock arm 151, so that the shifter rod 149 is moved to bring the notch 168 thereon into engagement with the pin 146 of the clutch shift lever W' . The upward movement of the shifter arm also places the spring 115 under tension, so

that as soon as the lug 117 of the stop arm S'' is moved out of the path of the lug 116, the shift lever S operates to move the sound box outwardly above the edge portion of the record. This outward movement of the sound box is arrested either by one or the other of the stops T or T', in accordance with the position of the shiftable stop T' which, as described, is placed in operative position to arrest the sound box when a small record is placed on the turn-table, but which is shifted to inoperative position by the lug 121 on the carriage G when a large record is placed thereon. At the end of the operation of the shifter mechanism, the rod n' is drawn downwardly by its spring 83 so that the arm n and track bar R are lowered to engage the pin N with the central opening in the record on the turn table, lower the sound box so that its needle engages the periphery of the record and also engages the segment nut 97 with the feed screw 95. At the end of the operation of the shifter mechanism, the stop M is lowered and arrests the shaft J and the parts operated thereby, at the same time the lever X (see Fig. 5) is shifted to release the switch X', and the latter is returned to closed position by its spring 171. The motor C then operates to rotate the turn table A and the feed screw 95 to reproduce the record that is in playing position on the turn-table.

At or near the end of the reproduction of the record, the nut 97 drops into the recess 160 of the feed-screw and the nut 159 on the lever 157 engages the threaded part 95' of the feed screw. This lever is then moved inwardly along the feed screw and its lug 156 is pressed against the lug 155 of the sliding rod 154, and, through the medium of the crank arm 153, shaft 152 and crank arm 151, the shifter 149 is operated to throw the clutch shifter W' and thereby re-engage the clutch W. At the end of this movement, the cam 167 on the shifter 149 engages the pin 166 and moves the shifter rod 149 to the position shown in Fig. 3, with the notch 168 out of engagement with the pin 146. The parts are then in position to rewind the actuating spring K of the shifter mechanism and are also in such a position that, at the end of this winding operation, the clutch can be disengaged by the movement of the stop-arm M and connecting link 148'. The machine will, unless its operation is arrested, again operate to play another record. While a record is being played, the next record can be selected, as described, from the full magazine; but if no selection is made by the user, the machine will automatically operate to play all the records in succession.

Preferably, however, means are provided for automatically arresting the machine at the end of the reproduction of each record.

For this purpose, the hub of the switch X' is provided with an arm 175 (see Figs. 5 and 6) which is pivoted to the end of a lever 176, the latter in turn being pivoted at 177 upon the rear face of the bracket 170. The bracket is provided with a vertical rib 178 on its rear face and a latch 179 is pivoted at 180 on this rib. The upper end of the latch, in the position shown in Fig. 7, extends between the bracket 170 and the right-hand end of the lever 176, and a spring 181 extends between the lower end of the latch and the right-hand end of the lever. At its lower end the latch is provided with a pin 182 which is arranged to co-operate with a hooked trip 183. The latch 179 is shown in inoperative position in the drawings, but in the extreme open position of the switch X', the right-hand end of the lever 176 will be raised to such an extent that the latch will be oscillated by the spring 181 to bring the pin 182 at its lower end into engagement with the trip 183 and to bring the upper end of the latch beneath the right-hand end of the lever 176 to thereby hold the switch 90 permanently in open position until the trip 183 is again actuated to release the latch.

The shifter X, while it operates to open the switch X', does not serve to shift it to its extreme open position, in which it is held by the latch 179. In consequence, this shifter X serves merely to stop the electric motor C during the operation of the shifter mechanism and does not permanently arrest the operation of the machine. For the latter purpose, a second shifter Y is provided that is pivotally mounted on a pin 184 that projects rearwardly from the bracket 170. One end of this shifter is provided with a pivoted dog y and a spring 185, extending between the dog and the lower portion of the bracket 170, holds the dog in engagement with a stop pin 186 on the end of the shifter arm Y. The opposite end of the shifter arm is provided with a cam-shaped nose y' which is arranged to be engaged by a laterally projecting pin 187 on the end of the lever k and which is held in engagement therewith by the spring 185.

At the end of the operation of the shifter mechanism, effected by the spring K, the lever k rests upon a stop or cross-bar 188 of the lower horizontal frame 2. As it approaches this lowermost position, the pin 187 depresses the right-hand end of the shifter y' and lifts its left-hand end against the tension of the spring 185. This moves the left-hand end of the shifter to the position shown in dotted lines in Fig. 5. During this movement, the dog snaps idly over a lug 189 on the lower end of the curved arm 172 of the switch. At the extreme lowermost position of the lever k, shown in dotted lines in Fig. 5, the pin 187 passes over the pointed end or nose of the cam y'. The 130

record on the turn-table is then reproduced and, at the end of the reproduction, as described, the clutch W is again re-engaged to raise the lever k and wind up the spring K. 5 But as soon as the lever is partly raised from the lowermost position to the position shown in full lines in Fig. 5, the pin will move above the point of the cam y' and the latter is so shaped that the spring 185 will then 10 quickly shift the lever Y, moving its left-hand end and dog y thereon downwardly from the position shown in dotted lines to that shown in full lines in Fig. 5. When moved in this direction, the dog will not 15 yield as it strikes the lug 189 on the arm 172, so that the latter is shifted to move the switch X' into its full open position and into engagement with the latch 179 which, at the same time, is returned into engagement with 20 the trip 183. The machine will then be permanently arrested until the trip 183 is again released. This trip can extend outside of the enclosing casing and be released by hand, if desired, but in the construction 25 shown, the forward end of the trip extends into a coin chute 190 formed upon the front face of the bracket 170 and is adapted to be released by the passage of a suitable coin therethrough. The parts in Figs. 5, 6 and 7 30 are shown in the position assumed just after the trip 183 has been released.

At each operation the sound box P is moved inwardly to a position adjacent the center of the turn-table and the record thereon, and is moved inwardly to a sufficient extent to play records having the longest grooves. But the length of groove varies considerably in different records, even of the same size, and terminates at 40 different distances from the center of the record. The innermost portion of the record groove, by its engagement with the needle of the sound box, tends to arrest the latter and cause disagreeable noises before the shifter mechanism described is operated to lift the sound box from the record. This is particularly apt to occur where the record groove is short and terminates some distance from the center of the record. To overcome 45 this difficulty, means are provided for lifting the sound box slightly to disengage its needle from the record shortly after the needle is brought into engagement with the innermost portion of the record groove. 50 For this purpose, the inner end of the track bar R is provided with a pin and slot connection with the arm n and is also connected thereto by a lift spring 109 and is adapted to be held in depressed position by a latch 55 110 mounted on the arm and having a nose 191 which, as hereinafter described, is adapted to overlap the inner beveled end of the track bar, during the operation of the machine. A trip bar 192 is pivoted at its

outer end to the outer end of the track bar 65 and the inner beveled end thereof is arranged to co-operate with a forwardly projecting, beveled lug 193 on the end of the latch 110. A spring 194, connected to the trip bar 192, normally holds it in raised position and in engagement with a stop pin 195 on the side of the track bar. The sound box, in addition to the lug r which projects over the track bar, has a bracket 196 secured to its lower portion. A horizontal 75 rod 197, which is preferably square in section, extends through a corresponding opening in the bracket 196 and the outer end of this rod is provided with a head 198. A spring 199, coiled about the rod 197 between 80 the bracket and the head, holds the rod and parts mounted thereon in the position shown, with a stop collar 200 on the inner end of the rod engaging the bracket. The head 198 is provided with a vertical recess within 85 which is arranged a shoe 201. The shoe is held against displacement by a screw 202 extending through the upper portion of the head and is pressed downwardly by a light spring 203 arranged within the recess of the 90 head. The head is also provided with a rearwardly projecting arm 204 having an inwardly projecting, inclined cam part 205 thereon. The inclined end of this cam is arranged above the trip bar 192 and below 95 the lug r on the sound box. When the sound box is in playing position, with its needle in engagement with a record, the shoe 201 also engages the record grooves and for this purpose is preferably provided with a 100 serrated lower face (see Fig. 12). To prevent the shoe from injuring the record, it is preferably formed of indurated fiber or the like.

When the sound box is at the inner end 105 of its movement, as shown in full lines in Figs. 8 and 9, the spring 109 holds the inner end of the track bar R above the nose 191 on the latch 110 and, in this position, the sound box is slightly raised by the engagement of the track bar with the lug r thereon, so that the needle of the sound box and the shoe 201 are out of contact with the record, as shown in Fig. 9. When the sound box is lifted, by the movement of the arm n 110 and the track bar, as already described, from the position shown in Fig. 9 to that shown in Fig. 10, the lug 122 thereon passes through the slot 123 of the cam plate 124 and considerable downward pressure is 115 exerted on the sound box. This pressure exerted on the track bar moves it relatively to the arm n and against the tension of the spring 109, so that its extreme inner end is engaged by the nose 191 of the latch 110. At the same time the pin 195 on the track 120 bar moves the trip bar 192 and brings its inner beveled end into engagement with the 125

inclined lug 193 on the latch. The latch remains in this position during the outward movement of the sound box and during the inward movement thereof when a record is played. During the reproduction of the record, the sound box needle and shoe 201 both engage the groove of the record and travel inwardly at the same rate. But when the needle and sound box are arrested by the innermost portion of the record groove, the shoe 201 is not arrested but continues to move inwardly. This movement is effected since the shoe is farther from the center of the record than the needle and, therefore, the spiral record groove continues to move the shoe after the needle and sound box have been raised. This relative movement of the shoe and parts connected thereto is effected against the pressure of the spring 199, and the cam 205, which is connected to the shoe, is forced beneath the lug *r* on the sound box and depresses the trip bar 192. The inner, beveled end of the trip bar then swings the latch 110 about its pivot, so that the nose 191 thereof is disengaged from the end of the track bar. The latter is then lifted by the spring 109 and raises the sound box slightly to disengage the needle from the record, as shown in Fig. 9. At the same time the shoe 201 is lifted out of engagement with the record and the spring 199 acts to return it and the parts connected thereto to normal position relatively to the sound box. It should be noted that these parts are arranged to automatically lift the sound box out of engagement with the record shortly after the needle reaches the innermost portion of the record groove and irrespective of the distance at which the record groove terminates from the center of the record. The construction is particularly advantageous in an automatic machine of the type set forth, since the rotation of the turn-table and the feed of the sound box must be sufficient to play the records having the longest record grooves. But with the automatic lifting mechanism described, when a record has a groove less than the maximum length, the latter portion of the inward movement of the sound box is effected with the needle out of contact with the record.

It is obvious that numerous changes may be made in the details set forth without departing from the essentials of the invention as defined in the claims.

I claim as my invention:—

1. A talking machine, the combination with means for rotating records in playing position and a cooperating support and a reproducer, of means for automatically shifting records of different sizes into and out of playing position on said support and means automatically controlled in accord-

ance with the sizes of the different records for effecting the cooperation of said reproducer therewith.

2. In a talking machine, the combination with a turn table and a sound box movable over said turn table, of record shifter mechanism for moving disc records of different sizes into and out of playing position on said turn table and sound box shifter mechanism automatically controlled in accordance with the sizes of the different records for effecting the cooperation of said sound box therewith.

3. In a talking machine, the combination with a rotatable record support and a reproducer cooperating therewith, of record shifting mechanism for moving records of different sizes into and out of playing position on said support, and sound box raising and shifting means automatically controlled in accordance with the sizes of the different records to variably position the sound box in engagement with the starting point of the record on said support.

4. In a talking machine the combination with a turn table for supporting disc records of different sizes, and a cooperating sound box, of mechanism for automatically raising and shifting the sound box and means automatically controlled in accordance with the size of the record on said turn table for varying the shifting position of said sound box.

5. In a talking machine the combination with a turn table for supporting disc records of different sizes, and a cooperating sound box, of shifter mechanism for moving disc records of different sizes into and out of playing position on said turn-table, mechanism for shifting said box to starting position, and means controlled by said record shifting mechanism for varying the movement of said sound box in accordance with the size of the record on said turn-table.

6. In a talking machine, the combination with means for rotating records in playing position and a reproducer, of shifter mechanism for moving records of different sizes into and out of playing position, and means automatically controlled in accordance with the sizes of the different records for variably positioning said reproducer to properly engage records in playing position.

7. In a talking machine, the combination with means for rotating records in playing position and a reproducer, of shifter mechanism for moving records of different sizes into and out of playing position, shifter mechanism for raising said reproducer and moving the same to starting position, and means controlled by said record shifter mechanism for varying the starting position of said reproducer in accordance with the size of the record in playing position.

8. In a talking machine, the combination with a sound box, of shifter mechanism for moving the disc records of different sizes into and out of playing position, shifter mechanism for raising said sound box and shifting the same to starting position, and stop devices controlled by said record shifting mechanism for variably limiting the movement of said sound box.
10. 9. In a talking machine, the combination with a rotatable support for records of different sizes and a cooperating reproducer, of shifter mechanism for raising said reproducer and moving the same to starting position, stop devices for variably limiting the movement of said sound box, and means for automatically adjusting said stop devices in accordance with the size of the record on said support.
20. 10. In a talking machine, the combination with a rotatable support for records of different sizes and a cooperating reproducer, of reproducer shifter mechanism including a spring-actuated shifter for moving said reproducer to starting position and adjustable stop devices automatically controlled in accordance with the size of the record in playing position for variably arresting the movement of the sound box.
30. 11. In a talking machine, the combination with a sound box, of shifter mechanism for moving disc records of different sizes into and out of playing position, sound box shifter mechanism including a spring actuated shifter for moving said sound box to starting position, and means controlled by said record shifter mechanism for variably arresting the movement of said sound box.
40. 12. In a talking machine, the combination with a turn-table and a cooperating sound box, of means for holding disc records of different sizes, a shifter for moving the records between said turn-table and said holding means, sound-box shifter mechanism including a spring actuated shifter for moving said sound box to starting position, and adjustable stop devices controlled by said record shifter for variably arresting the movement of said sound box.
50. 13. In a talking machine, the combination with a rotatable support for records of different sizes and a reproducer, of shifter mechanism cooperating with said reproducer to automatically change the needle thereon and means automatically controlled in accordance with the size of the record on said support for varying the starting position of said reproducer.
60. 14. In a talking machine, the combination with a sound box, of means for holding disc records of different sizes, a needle magazine, and shifter mechanism for automatically moving the records of different sizes into and out of playing position, changing the needle of said sound box and variably mov-
- ing the latter to starting position, and means for automatically controlling said shifter mechanism in accordance with the size of the record in playing position.
15. In a talking machine, the combination with a turn-table for rotating disc records and a cooperating sound box, of means for holding disc records of different sizes, a needle magazine, and shifter mechanism automatically controlled in accordance with the sizes of the different records for moving the latter between said holding means and said turn-table, changing the needle of said sound box, and variably moving the latter to starting position in engagement with the record on said turn-table.
16. In a talking machine, the combination with means for rotating records in playing position, and a cooperating reproducer, of shifter mechanism for moving records of different sizes into and out of playing position, means for disengaging the record in playing position from said shifter mechanism, and means for raising the reproducer and variably adjusting the starting position thereof, said means being automatically controlled in accordance with the size of the record in playing position.
17. In a talking machine, the combination with a turn-table for rotating disc records and a cooperating sound box, of holding means for a plurality of disc records of different sizes, a shifter for moving the records between said holding means and said turn-table, means for disengaging the record on the turn-table from said shifter, means for raising the sound box and moving the same to starting position, and stop devices controlled by said shifter for variably arresting the movement of said sound box.
18. In a talking machine, the combination with a turn-table for rotating disc records and a cooperating sound box, of holding means for a plurality of disc records of different sizes, a shifter for moving the records between said holding means and said turn-table, means for centering and holding a record in playing position on said turn-table, means for moving said shifter out of engagement with the record on the turn-table, and means automatically controlled in accordance with the different sizes of the records for engaging the sound box with the starting portions of the records on said turn-table.
19. In a talking machine, the combination with a turn-table for rotating disc records and a sound box, of means for holding disc records of different sizes, a shifter for moving the records into and out of playing position on said turn-table, a center pin for holding the records in place on said turn-table, a shifter for raising the sound box, and moving the same laterally, means controlled by said record shifter for vari-

- ably positioning the sound box in engagement with the starting portions of records of different sizes on said turn-table, and mechanism for actuating said center pin 5 and said record and sound box shifters.
20. In a talking machine, the combination with means for rotating records in playing position and a cooperating reproducer, of means for holding a plurality of records of 10 different sizes, adjustable means for selecting a record, and shifter mechanism for moving the selected record to playing position and for variably positioning said reproducer in accordance with the size of the selected record and in engagement with the 15 starting portion thereof.
21. In a talking machine, the combination with means for rotating records in playing position and a cooperating reproducer, of 20 means for holding a plurality of records of different sizes, means for manually adjusting said holding means to select a record, shifter mechanism for moving records between said holding means and playing position 25 and for automatically adjusting said holding means, and reproducer shifting mechanism automatically controlled in accordance with the size of the record in playing position for variably positioning the 30 reproducer in engagement with the starting portion of the record.
22. In a talking machine, the combination with means for rotating records in playing position and a reproducer, of a plurality of 35 records of different sizes, holding means therefor, and shifter mechanism automatically controlled in accordance with the sizes of the different records for moving the same into and out of playing position and for 40 effecting the cooperation of said reproducer therewith.
23. In a talking machine, the combination with means for rotating records in playing position and a reproducer, of a plurality of 45 records of different sizes, holding means therefor, means for adjusting said holding means to select a record, a shifter for moving said records between said holding means and playing position, a shifter for said 50 reproducer, and means for variably positioning said reproducer automatically controlled in accordance with the size of the record in playing position.
24. In a talking machine, the combination 55 with a reproducer, of a rotatable turn-table support for disc records, a center pin for holding records in position thereon, a plurality of disc records of different sizes, holding means therefor, means for adjusting said holding means to select a record, a shifter for moving the records between said holding means and said turn-table, a shifter for said reproducer, and means controlled by said record shifter for variably positioning said 60 reproducer in accordance with the size of the 65
- record on said turn-table and in engagement with the starting portion thereof.
25. In a talking machine, the combination with a reproducer, of a plurality of magazines respectively adapted to hold records 70 of different sizes respectively, and means for automatically shifting the different sized records into and out of playing position and for variably shifting said reproducer to effect the cooperation thereof with different 75 sized records in playing position.
26. In a talking machine, the combination with means for rotating disc records in playing position and a cooperating reproducer, of a plurality of magazines respectively 80 adapted to hold disc records of different sizes, and shifter mechanism for moving the records between said magazines and playing position and for effecting the cooperation of said reproducer therewith. 85
27. In a talking machine, the combination with means for rotating disc records in playing position and a cooperating reproducer, of a plurality of relatively large and small disc records, two magazines, one for holding 90 the records of each size, means for operating each of said magazines to select one of the records therein, and shifter mechanism for moving the selected record to and from playing position and for effecting the cooperation 95 of said reproducer therewith.
28. In a talking machine, the combination with means for rotating disc records in playing position and a cooperating reproducer of a plurality of relatively large and small 100 disc records, two magazines, one for holding the records of each size, means for operating said magazines to select one of the records therein, shifter mechanism for moving the selected records into playing position and 105 back to its magazine, and means for raising said reproducer and for variably positioning the same in accordance with the size of the record in playing position and in engagement with the starting portion thereof. 110
29. In a talking machine, the combination with means for rotating disc records in playing position and a cooperating reproducer of a plurality of relatively large and small disc records, two magazines, one for holding 115 the records of each size, shifter mechanism for moving said records between said magazines and playing position, shifter mechanism for raising and moving said reproducer, and means controlled by said record 120 shifter mechanism for variably adjusting said reproducer to starting position in accordance with the size of the record in playing position.
30. In a talking machine, the combination 125 with means for rotating disc records in playing position and a cooperating reproducer, of a plurality of relatively large and small disc records, two magazines, one for holding the records of each size, a shifter having 130

- means for engaging a large and a small record, means for operating said shifter to move a record from playing position back to its magazine and move a record from the other magazine to playing position, and means for effecting the co-operation of said reproducer with different sized records in playing position.
31. In a talking machine, the combination with a turn-table and a cooperating sound box, of two magazines for holding large and small records respectively, and shifter mechanism for alternately moving large and small records from said magazines into playing position on said turn-table and for effecting the cooperation of said sound box therewith.
32. In a talking machine, the combination with a turn-table and a cooperating sound box, of two magazines for holding large and small records respectively, a shifter having holders for engaging a large and a small record, means for alternately moving said shifter in opposite directions to return a record to one of said magazines and place a record from the other magazine in playing position on said turn-table, and means for effecting the co-operation of the reproducer with different sized records in playing position.
33. In a talking machine, the combination with a turn-table and a cooperating sound box, of two magazines for holding large and small records respectively, said magazines being shiftable to select a record therein, a shifter having holders for engaging a large and a small record, means for alternately moving said shifter in opposite directions to return a record to one magazine and move a record from the other magazine onto said turn-table, a shifter for raising and moving said sound box, and means controlled by said record shifter for variably determining the starting position of said sound box in accordance with the size of the record on said turn-table.
34. In a talking machine, the combination with a turn-table and a cooperating sound box, of two magazines for holding large and small records respectively said magazines being shiftable to select a record therein, a shifter having holders for engaging a large and a small record, means for alternately moving said shifter in opposite directions to return a record to one magazine and move a record from the other magazine onto said turn-table, means for disengaging the record on the turn-table from said shifter, and means for effecting the cooperation of said sound box therewith.
35. In a talking machine, the combination with a turn-table and a cooperating sound box, of two magazines for holding large and small records respectively said magazines being shiftable to select a record therein, a shifter having holders for engaging a large and a small record, means for alternately moving said shifter in opposite directions to return a record to one magazine and move a record from the other magazine onto said turn-table, shifter mechanism for raising and laterally moving said sound box to starting position and stop devices controlled by said record shifter for variably arresting the movement of said sound box.
36. In a talking machine, the combination with a turn-table and a cooperating sound box, of two magazines for holding large and small records respectively said magazines being shiftable to select a record therein, a shifter having holders for engaging a large and a small record, means for alternately moving said shifter in opposite directions to return a record to one magazine and move a record from the other magazine onto said turn-table, shifter mechanism for raising and laterally moving said sound box to starting position and stop devices controlled by said record shifter for variably arresting the movement of said sound box.
37. In a talking machine, the combination with a turn-table and a cooperating sound box, of two magazines for holding large and small records respectively said magazines being shiftable to select a record therein, a shifter having holders for engaging a large and a small record, means for alternately moving said shifter in opposite directions to return a record to one magazine and move a record from the other magazine onto said turn-table, a shifter for raising and moving said sound box, and means controlled by said record shifter for variably determining the starting position of said sound box in accordance with the size of the record on said turn-table, means for raising said sound box, a spring-actuated shifter for moving the same laterally to starting position, adjustable stop devices for variably arresting the lateral movement of said sound box, and a lug on said record shifter for adjusting said stop devices.
38. In a talking machine, the combination with means for rotating records in playing position and a cooperating reproducer, of a motor for actuating said record rotating means, shifter mechanism for moving records into and out of playing position and for adjusting said reproducer, a clutch for connecting said motor to said shifter mechanism, a trip device actuated by said shifter mechanism for disengaging said clutch, a feed-screw for moving said reproducer over the record in playing position, and a second trip device actuated by said feed screw at the end of the reproduction of a record for engaging said clutch.
39. In a talking machine, the combination with means for rotating records in playing

position and a cooperating reproducer, of a motor for actuating said record rotating means, shifter mechanism for moving records into and out of playing position and 5 for adjusting said reproducer, a clutch for connecting said motor to said shifter mechanism, means actuated before and at the end of the reproduction of a record for disengaging and engaging said clutch, and means 10 actuated by the initial movement of said shifter mechanism for stopping said motor.

40. In a talking machine, the combination with means for rotating records in playing position and a cooperating reproducer, of 15 a motor for actuating said record rotating means, shifter mechanism for moving records into and out of playing position and for adjusting said reproducer, a clutch for connecting said motor to said shifter mechanism, 20 means actuated by said shifter mechanism for disengaging said clutch, a feed-screw for moving said reproducer over the record in playing position, and means actuated by the initial movement of said shifter mechanism 25 for stopping said motor.

41. In a talking machine, the combination with a rotatable record support and a cooperating reproducer, of shifter mechanism for moving records into and out of playing 30 position on said support and for raising and moving said sound box to starting position, an electric motor geared to said turn-table, a clutch for connecting said motor to said shifter mechanism, means acting between 35 the reproduction of records for throwing said clutch into and out of operation, a switch for starting and stopping said motor, and means actuated by said shifter mechanism for opening said switch.

40 42. In a talking machine, the combination with a rotatable record support and a cooperating reproducer, of shifter mechanism for moving records into and out of playing position on said support and for raising 45 and moving said sound box to starting position, an electric motor geared to said turn-table, a clutch for connecting said motor to said shifter mechanism, means acting between the reproduction of records for throwing 50 said clutch into and out of operation, a switch for starting and stopping said motor, means actuated by said shifter mechanism for opening said switch and a releasable catch for holding said switch in open 55 position.

43. In a talking machine, the combination with a rotatable record support and a cooperating reproducer, of shifter mechanism for moving records into and out of playing 60 position on said support and for raising and moving said sound box to starting position, an actuating motor geared to said turn-table, an actuating spring for said shifter mechanism, winding means for said spring, a

clutch for connecting said winding means to 65 said motor, means controlled by said shifter mechanism for disengaging said clutch and means controlled by the movement of said sound box for engaging said clutch.

44. In a talking machine, the combination 70 with record rotating means and a co-operating reproducer, of a spring actuated lifter for disengaging the reproducer from the record, a latch for holding said lifter inactive, and means operated by said record rotating 75 means and controlled by the stopping of the reproducer at the end of the record groove for tripping said latch.

45. In a talking machine, the combination 80 with a record, record rotating means and a cooperating reproducer, of spring actuated means for lifting the reproducer from the record, a latch for holding said means inactive, and means mounted on the reproducer adapted to engage the record and automatically 85 controlled by the length of the record groove to trip said latch and throw said lifting means into operation.

46. In a talking machine, the combination 90 with a record, record rotating means and a cooperating reproducer, of a spring-actuated lifting bar for said reproducer extending beneath the path of movement thereof, a latch for holding said lifting bar in depressed position, a trip bar for said latch, and a part 95 mounted on said reproducer for automatically actuating said trip bar when said reproducer reaches the end of the groove of said record.

47. In a talking machine, the combination 100 with means for rotating records in playing position and a cooperating reproducer, of shifter mechanism for moving records into and out of playing position and for moving said reproducer to starting position and into 105 engagement with the record in playing position, means for feeding said reproducer to a terminal position, and means for disengaging said reproducer from the record at different distances from said terminal position 110 and in accordance with the varying lengths of the grooves of the records.

48. A phonograph for automatically playing different records in succession, combining a turn-table; a sound-box having a stylus; means for conveying a succession of differently sized records to said turn-table; and automatic mechanism for determining the initial position of said stylus before the lowering thereof to compensate for the different 120 sizes of the records.

49. In an attachment for talking machines, the stylus of a talking-machine, and automatic means to determine the starting point of said stylus for playing a record of a 125 given diameter, and automatic means to determine the starting point of said stylus for playing a record of a larger diameter.

50. In a talking machine, the combination with record rotating means, and a co-operating reproducer, of a spring-actuated lifter for disengaging the reproducer from the record, latching means for holding said lifter inactive, operated by said record rotating means and controlled by the stopping of the reproducer at the end of the record groove for releasing the said lifter, and shifter mechanism for resetting said lifter and for returning the reproducer to starting position.

JOHN GABEL.
